US0D1062901S

(12) **United States Design Patent** (10) **Patent No.:** **US D1,062,901 S**
(45) **Date of Patent:** **** Feb. 18, 2025**

(54) **ROTATABLE TOY**

(71) Applicant: **Xiaolin Peng**, Meizhou (CN)

(72) Inventor: **Xiaolin Peng**, Meizhou (CN)

(**) Term: **15 Years**

(21) Appl. No.: **29/954,840**

(22) Filed: **Jul. 30, 2024**

(30) **Foreign Application Priority Data**

Jul. 23, 2024 (EM) 015067280-0001

(51) **LOC (15) Cl.** **21-01**

(52) **U.S. Cl.**

USPC **D21/455**
